CLAIM

The ornamental design for a cloth purse, as shown and described.

DESCRIPTION

FIG. 1 is a front perspective view of the cloth purse of the instant invention;

FIG. 2 is a rear plan view thereof;

FIG. 3 is a front plan view thereof;

FIG. 4 is a right plan view thereof;

FIG. 5 is a left plan view thereof;

FIG. 6 is a top view thereof; and,

FIG. 7 is a bottom view thereof.

The broken line showing of a cloth purse is included for the purpose of illustrating environmental structure and forms no part of the claimed design.
